UNITED STATES PATENT OFFICE.

ARTHUR H. SYMONS, OF CHICAGO, ILLINOIS, ASSIGNOR TO SYMONS CLAMP & MFG. COMPANY, OF CHICAGO, ILLINOIS, A CORPORATION OF ILLINOIS.

FORM CLAMP.

Application filed March 12, 1928. Serial No. 260,909.

The invention relates to clamps for holding together the separable sections that form a mold into which concrete or other plastic material is poured and set in the construction of buildings and other structures, and more particularly to those clamps which comprise a series of independent or separate units each consisting of a single bar which is adapted to be placed against one of the sections of the mold and has a longitudinal series of spaced wedge-slots at one end thereof, a bracket which is rigidly secured to the other end of the bar and has formed therein a transversely extending chamber for receiving and holding in so called overlapped or intersecting relation the slotted end of the adjoining bar, and a wedge which is adapted to extend through slots in the bracket and one of the slots in the said adjoining bar and is operative to effect relative movement of the two bars to urge or clamp them against their respective sections so as to hold the latter in connected relation during the pouring and setting periods.

One object of the present invention is to provide a clamp of this character in which the brackets and the wedge-slots in the brackets are so formed and arranged that, when the bars are placed in their operative position against the sections of the mold, there is always available without inserting the bars, one combination of slots through which the wedges may be inserted.

Another object of the invention is to provide a clamp in which the units are interchangeable and may be assembled in either an upright or an inverted position without effecting or changing the adjustability of the clamp.

A further object of the invention is to provide a one-piece clamping bracket for a bar of a form or column clamp, which is of new and improved construction, embodies as an integral part thereof an anvil which may be used to hammer against when shifting the bracket into its operative position, and is reinforced so as to efficiently and effectively withstand the comparatively great pressures or forces to which it is subjected during use.

A still further object of the invention is to provide a column clamp of the aforementioned type, in which the brackets offer a maximum amount of adjustability and are

compact so that the units may be conveniently and economically handled during shipping.

Other objects will be manifest as the description proceeds.

The invention consists in the several novel features hereinafter set forth and more particularly defined by the claims at the conclusion hereof.

In the drawing which accompanies and forms a part of this specification and in which like numerals of reference denote corresponding parts throughout the several views:

Figure 1 is a transverse sectional view of a mold to which is applied a clamp embodying the invention.

Figure 2 is a plan view of one of the units, that is, one of the bars and the bracket attached thereto.

Figure 3 is an enlarged section taken on line 3—3 of Figure 2.

Figure 4 is a side view of the bracket shown in Figures 2 and 3.

Figure 5 is a perspective view of one of the brackets.

Figure 6 is an end view showing the anvil at the end of the bracket.

The invention is exemplified in a clamp for securing together in squared relation the four sides or sections of a mold for forming a column of concrete, cement, or any other plastic material. The sections are separable and together form a rectangular mold in which the concrete is poured and allowed to set, as well understood in the art. The clamp which forms the subject matter of the present invention comprises four bars 10 which are made of any desired length and are preferably formed of strap iron. One end of each bar is provided with a longitudinal series of transverse openings or slots 11 which are spaced equidistantly and are adapted to receive a substantially V-shaped wedge 12. The other ends of the bars are provided with brackets 13 which are adapted to receive and hold the slotted ends as shown in Figure 1. In applying the clamp to a mold, the bars 10 are positioned against the sides or sections respectively and in such a manner that the slotted ends project outwardly from the corners of the mold and intersect the brackets 13. The slotted ends of the bars are held against outward movement by the bracket and the

latter have slots as hereinafter described, which receive and support the wedges 12 and cooperate therewith to effect relative movement of the bars and urge them into 5 clamping relation around the sections.

Each bracket 13 is formed of a one-piece casting and comprises a substantially square plate 14 which fits against one face of the extreme unslotted end of the bar with which 10 the bracket is associated. The plate is rigidly held in this position by a rivet 15 which extends through aligned holes 16 and 17 punched in the bar and plate respectively. At the end margin of the plate is an end wall 18 which is coextensive with the end of the bar and abuts thereagainst so as to prevent 15 the bracket from rotating or turning relatively to said bar. Projecting outwardly from the wall 18 and disposed adjacent the end of the bar is an arm or holding member 19 for receiving the slotted end of the adjacent bar. This arm extends at right angles to the plate and bar and comprises a lower wall 20 and an upper wall 22. These walls 20 25 are spaced apart by an end wall 21 to form a transversely elongated chamber or channel 23 which opens toward the riveted end of the bar and is adapted to receive the slotted end of the adjoining or contiguous bar. 30 The latter is insertable edgewise or laterally into the chamber and is longitudinally slideable therein in response to the action or operation of the wedge 12 as will appear hereafter. The lower wall 20 is flush with the 35 top surface of the bar so that the slotted bar-end may be laid upon the unslotted and riveted end and slid directly onto said lower wall and into the chamber 23. The walls 20 and 21 are coextensive and the sides thereof 40 project laterally with respect to the side edges of the bar and terminate at equal distances from the longitudinal center of the bracket and bar.

The upper wall 22 has formed therein a 45 pair of transversely extending slots 24 which extend on either side of the longitudinal center of the bracket and bar and are equidistantly spaced therefrom. These slots are aligned with a pair of slots 25 formed in 50 the lower wall 20 and form therewith a pair of sockets for receiving and supporting one of the wedges 12. The upper wall has also formed therein a pair of open-ended slots 26. These slots are formed in the ends of 55 said upper wall and are spaced equal distances from the longitudinal center of the bracket. Slots 26 are aligned with a pair of open-ended slots 27 which are formed in the ends of the lower wall 20. The slots 26 and 60 27 at the side of the bracket remote from the mold operate in a similar manner to the slots 24 and 25 to form sockets for receiving the wedge 12, it being obvious that the open-ended slots at the other side are inoperative 65 in this position of the bracket, although

when the bracket is used in an inverted position they are operative. The slots in the upper wall and consequently the slots in the lower wall are spaced apart distances which are different than those between the slots 11 70 with the result that there is always available one combination of slots (24, 11, 25 or 26, 11, 27) through which the operator may insert a wedge and upon driving it down, effect a relative movement of the arm and bar for 75 clamping purposes. Since the arm is arranged so that it terminates at equal distances from the longitudinal center of the bar and bracket and since the wedge slots in the arm are similarly arranged, the bracket 80 may be used equally as well in an inverted position as in an upright position. This operates to facilitate assembly of the clamp units and furthermore makes it possible to arrange the bars in parallelism by having 85 one set of diagonally opposite brackets in an upright position and the other set in an inverted position. A characteristic of extending the sides of the arm 19 beyond the side edges of the bar and utilizing open-ended wedge slots is that the bracket offers a maximum amount of adjustability and still is compact so that it may be conveniently handled during shipping.

To reinforce and strengthen the parts of the arm that contact with the wedge, the outer faces of the walls 20 and 22 are provided adjacent the slots with pads or raised portions 28. The end wall 21 is disposed at the outer end of the bracket and forms an 90 abutment for the outer edge of the bar that extends through the chamber 23. The inner end of the lower wall 20 is provided adjacent the ends of the wall 18 with a pair of lugs 29. The latter extend at right angles to said 95 wall 18 and form therewith a socket in which the unslotted end of the bar that is associated with the bracket fits and is locked against relative movement.

To prevent the upper and lower walls of 100 the bracket from being forced apart or broken and to strengthen the connection between the plate 14 and the arm, a pair of U-shaped reinforcing members 30 and 31 are provided. These members are integral with 105 the bracket and extend around the upper end and lower walls as illustrated in Figures 4 and 5. The members 30 and 31 are positioned adjacent the outer ends of the arm and between the wedge slots. The inner 110 ends of the lower legs of these members extend towards each other, as at 32, and then outwardly along the side edges of the plate 14 to form reinforcing ribs 33. To permit 115 the bracket to be hammered into place, an anvil 34 is formed on the back of the arm. This anvil is formed as an integral part of 120 the end wall 21 and operates to distribute the hammer blows to the various parts of the casting from which the bracket is made 125 130

so that no injury to the latter will result. Ribs 35 extend across the central portions of the walls 20 and 22 and are connected to the anvil so as to assist the latter in distributing the hammer blows and reinforcing the bracket.

The clamp is operated as follows: The bars 10 are arranged against the sides of the mold respectively in such a manner that 10 the slotted ends cross or intersect the end edges of the unslotted bar-ends at the corners of the mold or form and project through the chambers 23 of the brackets as illustrated in Figure 1. The bars are then manually shifted in a longitudinal direction as far as possible so that the brackets operate to jam the bars into close contact or abutting relation with the mold-sections. Thereafter the wedges 12 are inserted through the 20 wedge slots in the brackets and bars to lock the bars against outward movement. These wedges are then driven down as far as possible to effect relative movement of the brackets and intersecting bar-ends which 25 results in the units being shifted towards each other and the inner edges of the bars which extend between the brackets being urged into their clamping position against the mold-sections. In this manner the mold 30 is held together while the concrete or plastic material is poured and allowed to set. When it is desired to remove the clamp, slight tapping on the small ends of the wedges operates to release the latter so that 35 they may be withdrawn and the bars dismantled.

The clamp herein disclosed consists of units which may be quickly assembled without selection or relative arrangement and 40 readily applied to the separable sections of a mold, includes a bracket of new and improved construction, and may be manufactured at a comparatively low cost.

While the clamp has been shown and described as consisting of four bars and utilizing brackets which have holding arms extending at right angles to the rivet bearing ends of the bars it is to be understood that more or less bars may be used depending 45 upon the shape of the mold or form and that the angle of the arms may be changed accordingly. It is also to be understood that the invention is not to be restricted to the details set forth, since these may be modified within the scope of the appended claims, without departing from the spirit and scope 55 of the invention.

Having thus described the invention, what I claim as new and desire to secure by Letters Patent, is:

1. A form clamp consisting of a series of independent units adapted to be placed against the sides of the form respectively, each unit comprising a bar having slots adjacent one end thereof and an arm rigidly

secured to its other end, said arm having an elongated transversely extending chamber formed therein together with wedge slots adjacent the central portion, the slotted ends of the bars fitting in the chambers of the 70 arms when the units are assembled, and wedge means extending through the slots in the bars and arms to clamp the bars around the form.

2. A form clamp consisting of a series of 75 independent units adapted to be placed against the sides of the form respectively, each unit comprising a bar having slots adjacent one end thereof and a transversely extending arm rigidly secured to its other end and projecting from both sides thereof, said arm having slots and an elongated transversely extending chamber formed therein, the slotted ends of the bars fitting in the 80 chambers of the arms when the units are assembled, and wedges extending through the slots in the arms and bars operative to 85 clamp said bars around the form.

3. A form clamp consisting of a series of 90 independent units adapted to be placed against the sides of the form respectively, each unit comprising a bar having slots adjacent one end thereof and a separately formed one-piece bracket rigidly secured to its other end, said bracket embodying an 95 arm projecting laterally from each side of the bar and having an elongated transverse chamber formed therein, the slotted ends of the bars fitting in the chambers of the arms when the units are assembled, and wedges 100 extending through the slots and bearing against portions of the arms to clamp the bars around the form.

4. A form clamp consisting of a series of 105 independent units adapted to be placed against the sides of the form respectively, each unit comprising a bar having slots adjacent one end thereof and a separately formed one-piece bracket rigidly secured to its other end, said bracket embodying an 110 arm disposed outwardly of the unslotted end of the bar and having closed wedge slots and a transverse chamber formed therein, the slotted ends of the bars fitting in the 115 chambers of the arms when the units are assembled, and wedges extending through the slots in the arms and bars operative to clamp said bars around the form.

5. A form clamp consisting of a series 120 of independent units adapted to be placed against the sides of the form respectively, each unit comprising a bar having slots adjacent one end thereof and a separately formed one-piece bracket having a socket formed therein in which the other end of 125 the bar fits and is rigidly secured, said bracket embodying an arm disposed outwardly of the socket and the unslotted end of the bar and having an elongated transversely extending chamber formed therein, 130

- the slotted ends of the bars fitting in the chambers of the arms when the units are assembled, and wedges extending through the slots and bearing against portions of 5 the arms to clamp the bars around the form.
6. A form clamp consisting of a series of independent units adapted to be placed against the sides of the form respectively, each unit comprising a bar having slots adjacent one end thereof and a bracket secured to the other end, having an arm projecting outwardly equal distances from the sides of the bar, said arm forming an elongated transverse chamber and having wedge slots 10 formed in both sides thereof, the slotted ends of the bars fitting in the chambers of the arms, and wedges extending through the slots in the arms and bars operative to clamp the bars around the form.
- 15 7. In a clamp of the character described, the combination of a pair of bars, the ends of which intersect each other, the end of one of the bars having formed therein a longitudinal series of slots, and means for holding the bars in clamping relation comprising a one-piece bracket embodying a plate secured to the end of the other bar, a wall connected to the plate and fitting against the end edge of said other bar to lock said plate and bar 20 against relative movement, and an arm connected to the wall and extending transversely with respect to said other bar, said arm having an elongated chamber formed therein in which the slotted bar-end fits and is longitudinally slideable, and wedge means extending through one of the slots and bearing against the arm.
- 25 8. In a clamp of the character described, the combination of a pair of bars, the ends of which intersect each other, the end of one of the bars having formed therein a longitudinal series of slots, and means for holding the bars in clamping relation comprising a one-piece bracket embodying a plate secured to the end of the other bar, a wall joined to the plate and fitting against the end edge of said other bar, and an arm connected to the wall and extending transversely with respect to said other bar, said arm com-

prising upper and lower walls and a side wall forming together an elongated chamber in which the slotted bar-end fits and is longitudinally slideable, the lower wall having lugs positioned to abut against the sides of said other bar to cooperate with the first mentioned wall in locking the bracket and bar against relative movement, and wedge means extending through one of the slots and bearing against the arm.

55 9. A one-piece bracket for use in securing together the intersecting ends of a pair of form clamping bars, comprising means at one end thereof forming a socket for receiving and confining against movement the end of one of the bars, and an arm disposed outwardly of said socket and projecting transversely, said arm having an elongated chamber for receiving the end of the other bar, and wedge slots formed therein.

60 10. A one-piece bracket for use in securing together the intersecting ends of a pair of form clamping bars, comprising means at one end thereof forming a socket for receiving and confining against movement the end of one of the bars, an arm disposed outwardly of said means and arranged so as to extend transversely with respect to said one bar, said arm comprising upper and lower walls and a side wall forming a chamber for receiving the end of the other bar, and a 65 U-shaped reinforcing member connected to and extending around said walls, said member having a portion thereof extending under and connected to the socket forming means.

70 11. A form clamp consisting of a series of independent units adapted to be placed against the sides of the form respectively, each unit comprising a bar having a cast one-piece bracket rigidly secured to one of its ends, said bracket having formed therein a transverse chamber for receiving the end of the adjoining bar and being provided with an integral anvil whereby it may be hammered into its operative position.

75 Signed at Chicago, Illinois, this 9th day of March, 1928.

ARTHUR H. SYMONS.
